5 Claims. (Cl. 307—88.5)

This invention relates to amplifiers, and more particularly to tunnel diode amplifiers which are sensitive to input signals of small amplitude. While not limited thereto, the invention is useful as an amplifier for sensing information stored in a memory of a high speed electronic data processing apparatus.

It is the general object of this invention to provide an improved tunnel diode amplifier capable of operation at very high speeds in responding reliably to an input signal of very small amplitude.

In one aspect the invention comprises two tunnel diodes connected in series with both a direct current bias and a high frequency alternating current bias applied across the series connected diodes. Means are provided for applying an input signal to the junction between the diodes. The combined peak bias is selected with relation to the characteristics of the diodes so that when one diode is in the high voltage state, the other is forced into the low voltage state, and vice versa. The diodes are further selected to have characteristics relative to each other so that in the absence of an input signal the bias voltages cause one diode to assume the high voltage state, and in the presence of an input signal the bias voltages cause the other diode to assume the high voltage state. In another aspect the invention includes additional means to render the amplifier sensitive to an input signal solely during predetermined intervals.

These and other objects and aspects of the invention will be apparent to those skilled in the art from the following more detailed description taken in conjunction with the appended drawings wherein:

FIGURE 1 is a circuit diagram of an amplifier constructed according to the teachings of the invention;

FIGURES 2a through 2e are charts of the characteristics of the tunnel diodes in the circuit of FIGURE 1 which will be referred to in describing the operation of the circuit; and

FIGURE 3 is a circuit diagram of an amplifier like that of FIGURE 1 which is additionally provided with means to render the amplifier sensitive to an input signal solely during predetermined intervals.

The amplifier shown in FIGURE 1 includes two tunnel diodes D_1 and D_2 connected in series between terminals 8 and ground, with the diodes poled in the same direction. The output of an alternating current bias source 10 is coupled across the series connected diodes by a connection from a V_{ac} terminal through a direct current blocking capacitor 12 to the point 8. The alternating current bias preferably has a frequency in the radio frequency range such that a half-cycle period is of the same order of magnitude as the rise time of the diodes. The output of a direct current bias source 14 is also coupled across the series connected diodes by a connection from a terminal $+V_{dc}$ through a low value resistor 16 to the point 8. Various bias power supply arrangements can be employed, and the configuration illustrated in FIGURE 1

2

is intended to represent one wherein the bias applied to the point 8 constitutes a direct current having a sinusoidal alternating current superimposed thereon. The direct current bias source 14 looking back from point 8 should preferably be one of low internal impedance so that the source appears to be a substantially constant voltage source.

An input terminal 18 is coupled through an input resistor R_i to the junction 20 between diodes D_1 and D_2 . The junction 20 is coupled through an output resistor R_o to an output terminal 22.

The construction and operation of the amplifier circuit of FIGURE 1 will be described with references to the charts of FIGURE 2 showing the current-voltage characteristic, under different bias and signal conditions, of the lower diode D_2 as modified by the effects of input resistor R_i and output resistor R_o . The upper diode D_1 may be viewed as a load for the lower diode D_2 , and its characteristic is thus shown reversed on the same axes.

FIGURE 2a shows the characteristics of diodes D_1 and D_2 in a relationship existing when a small instantaneous voltage V_1 is applied across the series diodes between point 8 and ground. The intersection 24 of the two curves defines the operating point wherein the voltage V_1 is divided between the two diodes and the current I_1 flows through both diodes. The operating point 28 is in the low voltage positive resistance region of the characteristic of both diodes.

FIGURE 2a also illustrates an important factor in the construction of the circuit of FIGURE 1, namely, that the peak current of the upper diode D_1 is less than the peak current of the lower diode D_2 by an amount 26. As the voltage across the diodes increases to the value V_2 shown in FIGURE 2b, the operating point is as represented at 28. It can be seen that, because diode D_1 has a lower peak current than diode D_2 , a further increase in the voltage V_2 will cause the negative resistance region of the diode D_1 to be encountered before the negative resistance region of the diode D_2 is reached. Therefore, as the voltage V_2 is increased further, the diode D_1 switches to its high voltage state and the diode D_2 remains in its low voltage state. This condition is illustrated in FIGURE 2c where the large voltage V_3 is applied, and the operating point is a point 30 in the high voltage positive resistance region of the characteristic of diode D_1 and is a point in the low voltage positive resistance region of the diode D_2 .

Therefore, FIGURE 2c illustrates the fact that, in the absence of an input signal applied to the input terminal 18 in the amplifier of FIGURE 1, the application of full instantaneous bias V_3 to the circuit always causes the upper diode D_1 to go to its high voltage state, while the lower diode D_2 remains in its low voltage state. The instantaneous voltage V_3 in FIGURE 2c represents the order of magnitude of the combined amplitude of the direct current and alternating current bias voltages. In the construction of the circuit of FIGURE 1, the amplitudes of the bias voltages are selected with relation to the characteristics of the diodes so that when peak bias voltage is applied, one diode (D_1) is forced to switch to its high voltage state, and the other diode (D_2) is forced to remain in its low voltage state.

The effect of the direct current bias V_{dc} and the superimposed alternating current bias V_{ac} may be viewed as causing the instantaneous bias across the diodes to oscillate between a minimum value V_1 as shown in FIGURE

$2a$ and a maximum or peak value V_3 as shown in FIGURE 2c. In the absence of an input signal on terminal 18, the lower diode D_2 always remains in a low voltage state, and no output signal is delivered to the output terminal 22.

The effect of an input signal will now be considered with references to FIGURES 2d to 2e. A positive input signal 32 applied to input terminal 18 causes a relatively greater current to flow through diode D_2 than flows through diode D_1 . The effect of the presence of an input signal is represented graphically in FIGURE 2d by shifting the characteristic curve of diode D_2 downwardly by an amount I_s representing the signal current. With an input signal present, the negative resistance region of the lower diode D_2 is encountered first as the voltage V_2 increases. Therefore the diode D_2 switches to its high voltage state, and the diode D_1 remains in its low voltage state to provide the peak bias operating point 34 in FIGURE 2e.

When an input signal 23 is present at the input of the circuit of FIGURE 1, the rapidly fluctuating bias supplied to the diodes from the sources 10 and 14 causes the lower diode D_2 to switch between its low and high voltage states. The resulting output signal 36 consists of a burst of oscillations corresponding in frequency to the frequency of the bias source 10. The output signal 36 is suitable for triggering a utilization circuit in the form of a monostable tunnel diode circuit; or the signal may be rectified, if desired, to provide an output pulse.

It is thus seen that, in the absence of an input signal 32, the upper diode D_1 switches and no output signal is developed. In the presence of an input signal 32, the lower diode D_2 switches and an output signal 36 is generated. A very small input signal 32 is effective to change the unbalance of the two diodes so that the lower diode D_2 switches and provides an output signal.

FIGURE 3 shows a small signal amplifier like that of FIGURE 1 but differing therefrom in that the alternating current bias is supplied to the amplifier only during predetermined intervals when an input signal may be present. The circuit of diodes D_1 and D_2 is the same as the corresponding circuit of FIGURE 1. The alternating current bias source 10, 12 in FIGURE 1 is replaced in FIGURE 3 by a gating circuit including series connected tunnel diodes D_3 and D_4 which are supplied with an alternating current bias V'_{ac} through capacitor 42, and are supplied with a direct current bias V'_{dc} through resistor 46. A gating signal input terminal 48 is coupled through a resistor R_g to the junction point 50 between the diodes D_3 and D_4 . The point 50 is coupled through a coupling resistor R_c to the terminal 8 of the amplifier.

In the operation of the circuit of FIGURE 3, the biases V'_{ac} and V'_{dc} are applied to the gating diodes D_3 and D_4 which are selected so that the upper diode D_3 switches between its low and high voltage states in synchronism with V'_{ac} . Diode D_4 remains in its low voltage state and no output appears at junction point 50. However, when an input gate pulse 52 is applied to the gate input terminal 48, the diodes are unbalanced in the other direction, and diode D_4 switches between its low voltage and high voltage states in synchronism with V'_{ac} . A burst of oscillations 54 occurring during the presence of the gate pulse 52 is thus generated at point 50 and is coupled through resistor R_c to the point 8 of the amplifier including diodes D_1 and D_2 .

The circuit of FIGURE 3 is especially useful in applications where the time of occurrence of the signal input pulse 56 can vary over a limited time range, and where it is desired to make the amplifier sensitive to the input signal solely during this time so that it will not amplify disturbances occurring at other times. The amplifier including diodes D_1 and D_2 is supplied with alternating current bias 54 (controlled by gate pulse 52) solely during the limited time range when an input signal 56 can be ex-

pected. The input signal 56 results in an output signal 58 in the manner that has been explained in connection with the amplifier circuit of FIGURE 1.

In the construction of the circuits of FIGURES 1 and 3, the frequency of the alternating current bias is selected to be sufficiently high with relation to the width of the input signal pulse so that at least one cycle of the bias occurs during the input pulse. The frequency of the alternating current bias is also selected to be such that a half cycle of the bias wave has a time period of the same order of magnitude as the rise time of the tunnel diodes. The rise time of a tunnel diode is the time required following the application of an input pulse for the diode to switch from its low voltage state to its high voltage state.

The tunnel diodes D_1 and D_2 are selected so that diode D_1 has a lower effective peak current than diode D_2 , as is illustrated in the chart of FIGURE 2a. The characteristic shown for diode D_2 is the actual characteristic of the diode D_2 alone as modified by the presence of input resistor R_1 and output resistor R_o . The desired characteristic shown for diode D_1 may be obtained by selecting a diode having the desired peak current, or may be obtained by modifying the characteristic of a given available diode by connecting a resistor in shunt with the diode and trimming its value until the desired effective peak current is obtained.

The circuits of FIGURES 1 and 3 are most sensitive to very small input signals when the effective peak current of diode D_1 is only very slightly less than the effective peak current of diode D_2 . However, if the difference in peak currents is made too small, the circuit will undesirably respond to unavoidable noise impulses present at the input. Therefore, the designer must chose a difference in peak currents giving him a suitable compromise between sensitivity to small signals and reliability of operation.

What is claimed is:

1. An amplifier comprising two tunnel diodes connected in series, means to apply a direct current bias across said series connected diodes, means to apply an alternating current bias across said series connected diodes, means to apply an input signal to the junction between said diodes, and means to derive an output signal from the junction between said diodes, said diodes being selected to have characteristics such that when instantaneous peak bias voltage is applied, one of the diodes must be in its high voltage state and the other must be in its low voltage state, said diodes being further selected to have different characteristics so that in the absence of an input signal of one polarity the peak bias voltage causes a particular one of the diodes to assume the high voltage state, and in the presence of said input signal the peak bias voltage causes the other one of the diodes to assume the high voltage state.

2. An amplifier as defined in claim 1 wherein said alternating current bias has a frequency such that a half period is of the same order of magnitude as the rise time of the diodes.

3. An amplifier as defined in claim 1 wherein said alternating current bias has a frequency such that one cycle has a duration less than the duration of the input signal.

4. An amplifier as defined in claim 1 wherein said alternating current bias is in the form of periodic bursts of radio frequency energy.

5. An amplifier as defined in claim 4 wherein said bursts are supplied by a gated circuit comprising two tunnel diodes connected in series, means to apply both direct current bias and alternating current bias across said series connected diodes, means to apply a gating pulse wave to the junction between said diodes, and means to couple bursts from the junction between said diodes in the gated circuit to said amplifier circuit.
